[57] CLAIM

The ornamental design for a candle holder, as shown and described.

DESCRIPTION

FIG. 1 is a perspective view of a candle holder showing my new design.

FIG. 2 is an enlarged top plan view thereof.

FIG. 3 is an enlarged bottom plan view thereof.

FIG. 4 is an enlarged side view thereof.

FIG. 5 is an enlarged, fragmentary, vertical cross-sectional view thereof, the candle holder being fragmen-tarily shown for convenience of illustration.
